SUPPORTING POLE FOR WALL RACKS, SHELVES, ROOM DIVIDERS AND THE LIKE

Carl B. Hinrichs, Charlotte, Mich., and Ronald W. Lane,
Chicago, Ill., assignors to Structural Products, Inc.,
Charlotte, Mich., a corporation of Michigan

Filed Sept. 26, 1962, Ser. No. 71,865

Term of patent 14 years

(Cl. D13—1)

Fig. 1

Fig. 2

Fig. 3

FIG. 1 is a side elevational view of a supporting pole for wall racks, shelves, room dividers and the like showing our new design.

FIG. 2 is a front perspective view of the pole.

FIG. 3 is an end view of the pole.

The dominant features of our design are shown in full lines in the drawing.

We claim:

The ornamental design for a supporting pole for wall racks, shelves, room dividers and the like, substantially as shown and described.
